JOHN J. BROWN, OF NEWARK, NEW JERSEY.

CONDENSING APPARATUS.

1,144,104.

Specification of Letters Patent. Patented June 22, 1915.

Application filed July 31, 1914. Serial No. 854,239.

To all whom it may concern:

Be it known that I, JOHN J. BROWN, a citizen of the United States, residing at Newark, in the county of Essex and State 5 of New Jersey, have invented an Improvement in Condensing Apparatus, of which the following is a specification.

In steam condensing plants, in which jet condensers are employed in conjunction with 10 cooling towers, spray ponds, or natural water supplies, it is frequently necessary to raise the cooling water to an elevation considerably above the condenser. There is no objection to this in instances where a dry 15 vacuum pump is employed, but the distance the cooling water may be raised when a hydraulic vacuum pump is employed is limited, because such pumps are not adapted for elevating water. Consequently, in such 20 instances where hydraulic vacuum pumps are employed, it is necessary to also employ additional pumps for raising the water to the required height, in order to deliver the same to the cooling tower, spray pond, or 25 the source of natural water supply from which the cooling water is taken.

The object of my present invention is to overcome this difficulty, making it possible, in a condenser system, to employ a hydraulic 30 vacuum pump, in all instances, irrespective of the height to which the cooling water must be raised to reach the cooling tower or spray pond, and in carrying out my invention the hydraulic air pump employed is connected directly to the injection pipe and 35 discharges under practically no head in an auxiliary tank, where the air and gases are liberated, and from which, by suitable pipe connections, due to the action of the vacuum 40 in the condenser, the portion of the injection water passed through the hydraulic air pump is returned to the injection pipe so that all of the cooling water is available 45 for condensing purposes, as will be herein- after more particularly described.

In the drawing, I have illustrated, in side elevation, a condensing apparatus in which my present invention is embodied.

Referring to the drawing, the condenser 50 employed is indicated at 10. This is a rectangular jet condenser, preferably similar to that shown and described in Letters Patent No. 978,697, granted December 13, 1910.

55 The condenser is suitably supported, be-

ing mounted at one end on a tail pump 11 of the centrifugal type, and adjacent the other end, upon columns 12, which, together with the pump 11, are fixed to any suitable foundation. An injection pipe 13 leads from the 60 reservoir 14 of a suitable cooling tower, spray pond, or source of natural water supply, to one end of the condenser 10. This pipe, adjacent the end at which it is connected to the condenser, is fitted with an injection valve 15, and, as is customary, to the discharge end of the tail pump 11 is connected a pipe 16, leading to the cooling tower or spray pond, and by which the injection water and condensed steam are returned to 70 the cooling tower, or spray pond, as the case may be.

As illustrated, I have shown the lower portion 33 of a cooling tower rising from the reservoir 14. The cooling tower, as will 75 be understood, may be of any construction known in the art, and as is usual the circulating water is supplied to the upper part thereof from the pipe 16 and delivered to a distributing system so that it may be divided and permitted to fall from the distributing system into the reservoir, passing through the cooling tower in its descent.

In carrying out my invention, I also employ a hydraulic air pump 17, preferably of 80 the rotary type. At one side, the pump 17 is connected by a pipe 18, which there is a valve 19 with the condenser 10, in order to withdraw the air and other non-condensable vapors from the condenser. The other side 85 of the pump 17 is connected by the pipe 20, in which there is a valve 21, to a nozzle 22 secured in the injection pipe 13, on the side of the valve 15 distant from the condenser 10.

The discharge of the pump 17 is indicated at 23, and as illustrated in the drawing, empties into an auxiliary tank or receptacle 24, of any desired construction, in which there is preferably provided a partition wall 90 25, although, as will be understood, this partition wall is not necessary to the operation of the apparatus.

The pipe 26 is connected at one end to a nozzle 27, on the injection pipe 13, between 105 the valve 15 and the condenser 10, and terminates at its other end below the water level in the auxiliary tank 24, within which, to this end of the pipe 26, an admission valve 28 is secured. This valve is fitted with a 110

float 29, there being suitable mechanism, connecting the same to the valve, for regulating its operation by the height of the liquid in the auxiliary tank 24.

5 As illustrated in the drawing, the tail pump 11 and the hydraulic air pump 17 may be driven by a suitable motor 30, to which they are both directly connected, although the manner in which these pumps are driven 10 forms no part of my present invention.

In the operation of this apparatus, as will be noted from the foregoing description and reference to the drawing, the hydraulic air pump is supplied directly from the injection pipe through the pipe 20, and the supply is controlled by regulating the valve 21. The pump 17, therefore, operates under substantially no head, and discharges into the auxiliary tank 24, where the air and gases 20 are liberated.

Under ordinary operating conditions, the vacuum at the point indicated at 31, is substantially the same as that within the condenser, or approximately twenty eight 25 inches, the point 31 being that at which the pipe 26 is connected to the injection pipe.

The vacuum at points in the injection pipes farther distant from the condenser, for example, at approximately the point 32, 30 where the pipe 20 is connected to the injection pipe, would probably not be more than four or five inches, and, due to this difference in the vacuum, that portion of the injection water supplied to the pump 17, 35 which may be approximately 10% thereof, after passing through the pump, where it is not raised more than three or four degrees in temperature, is returned from the auxiliary tank 24, where it is discharged by the 40 pump, through the pipe 26 to the injection pipe 13, where, with the other injection or cooling water, it enters the condenser and is available for condensing purposes.

The valve 28, with its float 29, operates so 45 as to prevent the liquid in the auxiliary tank 24 from falling below a pre-determined level in order to prevent any air from passing through the pipe 26 and entering the condenser, and inasmuch as the valve 28 is 50 partially closed at all times, there will be a considerable difference in vacuum on the opposite sides thereof, which also assists in the operation of the apparatus.

I claim as my invention:

55 1. A steam condensing plant comprising a jet condenser, a source of injection water therefor, a hydraulic air pump, a connection from the condenser to the pump for withdrawing the gases from the interior of the 60 condenser, a connection from the said pump to the source of injection water, a receptacle independent of the source of injection water and into which the said pump discharges under a free head, and a pipe connection between the said receptacle and the interior

of the condenser so that a portion of the injection water is first passed through the said pump to withdraw the gases from the condenser and is then returned from the said receptacle through the said pipe connection to the condenser and employed for condensing purposes. 70

2. A steam condensing apparatus comprising a jet condenser, a source of injection water, an injection pipe leading to the condenser, a discharge pipe leading from the same, a hydraulic air pump, a connection between the said injection pipe and the said pump through which water is supplied to the pump to operate the same, a receptacle independent of the source of injection water and into which the pump discharges under a free head, a pipe connection between the said receptacle and the said injection pipe through which the water that is passed through the pump to operate the same is returned from the said receptacle to the said injection pipe to be utilized for condensing purposes before being returned to the said source of injection water. 80 85 90

3. A steam condensing apparatus comprising a jet condenser, a cooling tower, an injection pipe leading from the cooling tower to the condenser, a tail pump, a discharge pipe leading from the tail pump to the cooling tower, a hydraulic air pump, a connection from the same to the said condenser for withdrawing the non-condensable vapors therefrom, a connection from the said injection pipe to the said pump through which a part of the injection water is passed to operate the pump, a receptacle independent of the cooling tower and into which the said pump discharges under a free head, and a pipe connection from the said receptacle to the said injection pipe at a point adjacent the said condenser and through which pipe connection the water for operating the pump is returned from the said receptacle to the said injection pipe to be utilized for condensing purposes. 95 100 105 110

4. A steam condensing apparatus comprising a jet condenser, a cooling tower, an injection pipe leading from the cooling tower to the condenser, a tail pump, a discharge pipe leading from the tail pump to the cooling tower, a hydraulic air pump, a connection from the same to the said condenser for withdrawing the non-condensable vapors therefrom, a connection from the said injection pipe to the said pump through which a part of the injection water is passed to operate the pump, a receptacle independent of the cooling tower and into which the said pump discharges under a free head, a pipe connection from the said receptacle to the said injection pipe at a point adjacent the said condenser and through which pipe connection the water for operating the pump is returned from the said receptacle to the 115 120 125 130

said injection pipe to be utilized for condensing purposes, an injection valve in the said injection pipe between the points at which part of the water is taken therefrom to operate the pump and that part at which the water from the pump is returned thereto, a control valve in the connection leading from the injection pipe to the pump, and a

control valve in the connection leading from the condenser to the pump.

Signed by me this 20th day of July, 1914. ¹⁰
